UNITED STATES PATENT OFFICE.

CHARLES W. BECK, OF DETROIT, MICHIGAN, ASSIGNOR TO THE BECK-FROST CORPORATION, OF DETROIT, MICHIGAN, A CORPORATION OF MICHIGAN.

PRIMING CUP.

Application filed January 24, 1921. Serial No. 439,620.

To all whom it may concern:

Be it known that I, CHARLES W. BECK, a citizen of the United States of America, residing at Detroit, in the county of Wayne 5 and State of Michigan, have invented certain new and useful Improvements in Priming Cups, of which the following is a specification, reference being had therein to the accompanying drawings.

10 This invention relates to priming cups and said invention consists in the structural features and arrangement of parts herein-after described and illustrated in the accompanying drawing, wherein;

15 Figure 1 is a sectional elevation with one embodiment of the invention;

Figure 2 is a view of the same in side elevation;

Figure 3 is a cross section on line 3—3 20 of Figure 1, drawn to an enlarged scale;

Figure 3^a is a sectional view similar to Figure 1 but showing a slight modification of the arrangement in Figure 1;

Figure 4 is a vertical sectional elevation 25 of another embodiment of the invention;

Figure 5 is a side view of the same;

Figure 6 is an enlarged sectional detail of a portion of Figure 4.

In these views, and referring more par- 30 ticularly to Figures 1 to 3 inclusive, I designates a priming cup having a reduced tubular downward extension which is in-

35 teriorly threaded just below the cup proper as indicated at 2. The lower end portion of said extension is preferably reduced to a somewhat greater extent than said threaded portion 2 and is exteriorly threaded as indicated at 3 to function as a nipple for mounting said cup. Said downward exten-

40 sion has an integral bottom member 4 having a discharge port 5. 6 is a valve member formed by a stem bevelled at the lower end to engage a valve seat formed by the margin of the port 5. Said stem projects upwardly

45 out of the cup 1 and is bent laterally to form a handle member 7 whereby said stem may be turned. At an intermediate point, the stem 6 is formed with an enlargement 8 which is screw threaded to engage the

50 threads 2 of the cup. The enlargement 8 may be produced upon the stem 6 in any desired manner preferably being formed by an upsetting process through a press operation. The enlargement 8 is formed at op- 55 posite sides of the stem 6 with vertical

passages 9 providing for the down flow of the priming fluid from the cup proper to the lower portion of said extension. From the preceding description, it will be evident that upon rotation of the stem 6 by means of its handle 7 the valve forming lower end of said stem will be raised or lowered from its seat due to the screw threaded engagement of the enlargement 8 with the threads 2 of the cup.

The construction shown in Figure 3^a conforms to the preceding description except for the fact that the valve forming stem 10 has a relatively short portion 10^a extending below the enlargement 10^b, the seat 10^c for said valve member being in this modification located in an interior portion of the tubular extension at the lower end thereof.

That form of the invention which is illus- 75 trated in Figures 4, 5 and 6 employs a valve member proper 11 and a valve stem 12 having an enlargement 13 at its lower end formed with a socket 14 wherein the upper end of said valve member is engaged. 80 Preferably the valve member is annularly grooved adjacent its upper end as indicated at 15 and a portion 16 of the enlargement 13 is swaged into the groove 15 to hold said valve member inserted in said socket. 85 Thus, the parts 11 and 12 together form a valve element corresponding to the element 6 of the Figure 1, which element has an intermediate portion enlarged and screw threaded to engage an interiorly threaded 90 portion of the cup. In this form of the invention, however, there is no increased restriction in the downward tubular extension below the interiorly threaded portion thereof. A ported valve seat engageable 95 by the lower end of the valve member 11 is formed by upsetting the lower end of the extension 17 as is indicated in dash lines at 18 in Fig. 4.

The described invention in any of its sev- 100 eral embodiments is adapted to be manufactured inexpensively and is of a standard and simple construction such as may not be easily damaged or rendered inoperative.

What I claim as my invention is:

1. In a priming cup, the combination with a cup forming member having a reduced downward extension formed with a discharge passage and having a valve seat in said passage and a threaded portion above 110

said seat, of a valve member having an enlarged portion threaded to engage said threaded portion of the extension, having an operating portion extended above said 5 cup forming member and having a portion extending below said threaded portion to engage said valve seat, the last mentioned portion being spaced from the surrounding wall of the discharge passage, the threaded 10 portion of the valve member having a passage therethrough for the down flow of the priming fluid from the cup proper.

2. In a priming cup, the combination with 15 a cup forming member having a reduced downward extension formed with a discharge passage and having a valve seat in said passage and a threaded portion above said seat, of a valve member having an enlarged portion threaded to engage said threaded portion of the extension, having an operating portion extended above said cup forming member and having a portion of relatively reduced diameter extending 25 downwardly from said threaded portion to engage said valve seat, the last mentioned portion being spaced from the surrounding wall of the discharge passage, the threaded portion of the valve member having a passage therethrough for the down flow of the 30 priming fluid from the cup proper.

3. In a priming cup, the combination with

a cup forming member having a reduced downward extension formed with a discharge passage, the upper portion of said extension being interiorly threaded and the 35 lower portion of said extension being formed with a valve seat, of a valve member comprising a portion engaging said seat and an operating portion having a handle above the cup forming member, said operating portion having an enlarged threaded portion engaging the threaded portion of said cup forming member and formed with a socket 40 engaged by the upper end of said valve member.

4. In a priming cup, the combination with 45 a cup forming member having a reduced downward extension formed with a discharge passage, said passage having an interiorly threaded portion and a valve seat 50 at a point below said threaded portion, of a valve member comprising upper and lower members, having permanent telescopic engagement, one of said members being formed with an enlargement screw threaded 55 to engage said threads of said extension, the lower element of the valve member being engageable with said valve seat and the upper element thereof being formed with an operating handle.

In testimony whereof I affix my signature.
CHARLES W. BECK.
